COMBINED MOP HEAD AND MOP HOLDER Francis O. Gibbs, 1812 Sullivan St.,
Greensboro, N.C. 27405

Filed Oct. 12, 1965, Ser. No. 87,445

Term of patent 3½ years

(Cl. D9—2)

FIG. 1

FIG. 2

FIG. 1 is a perspective view of a combined mop head and mop holder showing my new design, and

FIG. 2 is a slightly enlarged right end elevational view of the combined mop head and mop holder of FIG. 1.

The side not shown has substantially the same appearance as the side shown, except as indicated in FIG. 1.

My design for the combined mop head and mop holder disclosed is characterized by the mop head, consisting of a socket and clamp plate portions as shown.

I claim:

The ornamental design for a combined mop head and mop holder, as shown and described.
